WALL MOUNTED JEWELRY BOX

Betty Jay Wertz, Owasso, Okla.
(412 S. Wyandotte, Bartlesville, Okla. 74003)

Filed Sept. 8, 1972, Ser. No. 287,502

Term of patent 14 years

Int. Cl. D6—04

U.S. Cl. D6—127

FIG. 1 is a right front perspective view of a wall mounted jewelry box showing my new design and shown in an open position; and

FIG. 2 is a right front perspective view thereof, shown in a closed position.

The left side and rear of the wall mounted jewelry box are plain and unornamented.

I claim:

The ornamental design for a wall mounted jewelry box, substantially as shown and described.
